[57] CLAIM

The ornamental design for a seaplane with pontoons, as shown and described.

DESCRIPTION

FIG. 1 is a side elevational view of a seaplane with pontoons showing my new design, the opposite side view being a mirror image of that shown;

FIG. 2 is a top plan view thereof;

FIG. 3 is a front elevational view thereof;

FIG. 4 is a rear elevational view thereof; and

FIG. 5 is a bottom plan view thereof.

FIG. 1

FIG. 2

FIG. 3

FIG. 4

FIG. 5
